(57) **CLAIM**

The ornamental design for a planter, as shown and described.

DESCRIPTION

FIG. 1 is a top front right perspective view of the planter of the present invention;

FIG. 2 is a bottom front right perspective view thereof;

FIG. 3 is a top view thereof;

FIG. 4 is a bottom view thereof;

FIG. 5 is a front view thereof;

FIG. 6 is a rear view thereof;

FIG. 7 is a left end view thereof; and,

FIG. 8 is a right end view thereof.

The portions of the planter illustrated in broken lines form no portion of the claim.
